UNITED STATES PATENT OFFICE

LEONARD KEBLER, OF BRONXVILLE, NEW YORK, ASSIGNOR TO WARD LEONARD ELECTRIC COMPANY, A CORPORATION OF NEW YORK

RESISTANCE UNIT

Application filed May 8, 1926. Serial No. 107,584.

This invention relates to resistance units and supporting means therefor.

In the form of unit herein disclosed, the resistive conductor is carried on an insulating tube or similar supporting body, and one object of the invention is to provide an improved means for supporting said tube or other body from one end thereof, and also to provide means whereby a plurality of such tubes may be supported in spaced relation to one another. A further object is to provide an improved resistance unit wherein the circuit terminals of the unit form a supporting means for the unit. A further object is to provide an improved means for supporting a plurality of resistance units in such a manner that each of the units may be readily removed from the support without disturbing the other units. Other objects include simplicity and strength of construction and economy of manufacture. Other objects and advantages of my invention, will appear from the following description taken in connection with the accompanying drawing, wherein

Fig. 1 is a side elevation, partly broken away, of the resistance unit and mounting.

Fig. 2 is a top plan view of the structure shown in Fig. 1.

Fig. 3 is a side elevation showing the manner of mounting a plurality of resistance units.

The body portion of the unit comprises a tube 10 of earthenware, porcelain or other suitable insulating material. The resistive conductor 13 is wound around the tube and held in place and protected by an insulating adhesive enamel coating 14, or other protective coating. Extending through the tube 10 at one side thereof is a conductor or lead 15 shown as a narrow strip of copper. The upper end of the strip 15 is bent outwardly and flat-wise through a notch 16 at the upper end of the tube 10. A few turns of the resistive conductor 13 is wrapped around the end of the strip which end is bent over on itself to firmly clamp the resistive conductor and also bent down against the tube 10. The lower end of the strip 15 extends out of the tube through a notch therein and is

bent laterally and has an enlarged end which is rigidly secured to an insulated supporting base or strip of fibre 21 by a metal eyelet 22, which extends through an opening in the end of the strip 15 and in the supporting base 21 and is headed over to clamp the parts together, the lower part of the rivet being in a countersunk portion of the base.

The other end of the resistance wire is connected to a metal terminal clip 23 which is formed of a piece of copper having a central lug 24 extending through a slot in the lower end of the tube and upwardly into the tube 10 and bearing against the inner wall of the tube. This lug 24 is stamped out from the body of terminal 23 and bent inwardly and upwardly as already stated and as shown in Fig. 1. The terminal 23 is also formed with an upwardly extending side lug 25 which extends upwardly along the outer wall of the tube 10. The resistive conductor 13 is wrapped around the lug 25 near its upper end; and the end is then bent over against itself to firmly clamp the resistive conductor. The insulating coating 14 is applied to and embeds the resistive conductor and the joints between the resistive conductor and the strip 15 and the lug 25. The terminal 23 is secured to the base 21 by an eyelet 28' which passes through openings in the terminal and base 21, the lower part of the base being countersunk to receive the rivet.

The conductor 15 and terminal 23, not only form circuit connections for the resistive conductor, but also serve to support and position the resistance unit.

Extending through the eyelets 22 and 28' are clamping and conducting screws 26, which are formed at their outer ends with unthreaded portions 27 of a reduced diameter, having openings 28 therein which receive the circuit conductors.

The units may be mounted upon a metal supporting plate or bar 29, and Fig. 3 shows the manner in which a plurality of units may be supported on the bar 29. The screws 26 of each of the resistance units extend through openings in the bar 29 and are insulated therefrom by means of bushings 30. A washer 31 engages each bushing and a nut 32 on

each of the screws locks the parts firmly in position.

I claim:

1. In a device of the class described, a metal plate, a row of resistance units carried thereby, each unit comprising a body member and resistive conductor wound thereon, terminal connections joined to said conductor and extending from the same end of said body member for supporting said body member, and means for supporting said connections and parts carried thereby on said plate, said means forming circuit terminals for said units.

2. In a device of the class described, a metal plate, a row of resistance units carried thereby, each unit comprising a body member and resistive conductor wound thereon, terminal connections joined to said conductor and extending from the same end of said body member for supporting said body member, and means for supporting said connections and parts carried thereby on said plate, said means forming circuit terminals for said units and comprising conducting screws passing through said connections and plate and insulated from said plate.

3. A resistance unit comprising a cylindrical member having an opening therethrough extending in an axial direction, a resistive conductor wound on said member, a metal member extending through and contacting with the inner wall of said opening and secured to said conductor at the outer end of said cylindrical member and projecting out sidewise from the inner end of said cylindrical member, and a metal member embracing the inner and outer walls of said cylindrical member at the inner end thereof over a portion of its circumference and secured to said conductor and also projecting out sidewise from the inner end of said cylindrical member, said metal members and projections being adapted to hold said unit in a fixed upright position and to form terminal connections.

4. A resistance unit comprising a cylindrical member having an opening therethrough extending in an axial direction, a resistive conductor wound on said member, a metal strip extending through said opening and contacting flatwise with the inner wall of said opening and embracing the outer wall and connected to said conductor at the outer end of said cylindrical member and projecting out sidewise from the inner end of said cylindrical member, and a sheet metal member embracing flatwise the inner and outer walls of said cylindrical member at the inner end thereof over a portion of its circumference and secured to said conductor, and also projecting out sidewise from the inner end of said member, said metal strip and sheet metal member and projections thereof being adapted to hold said unit in a fixed upright position and to form terminal connections.

5. A resistance unit comprising a cylindrical member having an opening therethrough extending in an axial direction, a resistive conductor wound on said member, a metal strip extending through said opening and contacting flatwise with the inner wall of said opening and embracing the outer wall and connected to said conductor at the outer end of said cylindrical member and projecting out sidewise from the inner end of said cylindrical member, a sheet metal member embracing flatwise the inner and outer walls of said cylindrical member at the inner end thereof over a portion of its circumference and secured to said conductor, and also projecting out sidewise from the inner end of said member, said metal strip and sheet metal member and projections thereof being adapted to hold said unit in a fixed upright position and to form terminal connections, an insulating base against which the inner end of said cylindrical member rests, and means for securing said projections to said base.

LEONARD KEBLER.
